ELECTRIC BOOT DRIER

Rudolph C. Schramm, Toledo, Ohio

Application November 10, 1952, Serial No. 319,772

3 Claims. (Cl. 219—19)

2

sleeves 21 cover the upper portions of the rods 8 to eliminate any danger of overheating the fabric of the boot as well as to facilitate rotating the frame in the boot for a more even distribution of heat from the coil to increase its drying efficiency.

In the operation of the device, the frame 5 is placed in a boot and plug 11 connected to a suitable electric circuit to heat the coil 15 which thus subjects the interior of the boot to a drying action.

10 The frame may be used either with or without the heating unit to dry the boot by placing the frame therein to hold the leg portion of the boot open and permit air to circulate therein.

15 From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. An electric boot drier comprising a frame composed of an upper ring, a lower ring and a plurality of vertical rods connected to the rings, insulators supported transversely of the frame by said rods, a heating unit supported in a vertical position in the frame by said insulators, an electric connector for the heating unit supported at the top of the frame, insulation sleeves on the rods adapted to space the frame centrally inside a boot, and a handle at the top of the frame for turning the latter in the boot.

2. An electric boot drier for vertical insertion in a boot comprising an upper ring and a lower ring and a plurality of vertical rods extending therebetween defining a frame for maintaining a boot to be dried in an open vertical position, insulators transversely supported in the frame by said rods, and a heating unit including an accessible electric connector supported by said insulators within said frame in a vertical and spaced relation relative to the vertical rods of said frame, said lower ring being of a smaller diameter than the upper ring for permitting ready insertion of said drier within a boot to be dried.

3. An electric boot drier for vertical insertion in a boot comprising an upper ring and a lower ring and a plurality of vertical rods extending therebetween defining a frame for maintaining a boot to be dried in an open vertical position, insulators transversely supported in the frame by said rods, a heating unit including an accessible electric connector supported by said insulators within said frame in a vertical and spaced relation relative to the vertical rods of said frame, and vertical insulators on said vertical rods for contacting the inner surfaces of a leg portion of a boot to be dried.
